UNITED STATES PATENT OFFICE.

THOMAS F. GAYNOR, OF LOUISVILLE, KENTUCKY, ASSIGNOR TO THE UNITED FIRE ALARM AND POLICE SIGNAL COMPANY, OF WEST VIRGINIA.

SYSTEM FOR SIGNALING AND COMMUNICATION.

SPECIFICATION forming part of Letters Patent No. 515,761, dated March 6, 1894.

Application filed December 30, 1891. Serial No. 416,604. (No model.)

To all whom it may concern.

Be it known that I, THOMAS F. GAYNOR, of Louisville, in the county of Jefferson, State of Kentucky, have invented certain new and useful Improvements in Systems for Municipal Signaling and Communication; of which the following is a description, taken together with the accompanying drawings, which form a part of this specification.

10 This invention relates to that class of electric signaling and telephonic mechanism known as police signal and telephone systems and which are adapted to suit the requirements of municipal police departments.

15 In the modern police system of signaling and communication the following features are deemed desirable, namely:—First. Means for automatically or manually telegraphing report signals and special calls from an outlying signal station to the central office and suitable devices at the central office to receive such calls, and send back to the station the requisite signals also. Second. Telephonic devices at the outlying station for 20 oral communication with the central office and corresponding telephonic mechanism at the central office to hold such communication. Third. "Answer back" mechanism at the outlying station to indicate to an officer 25 after he makes his "report" calls that he is expected to report orally for some special instructions from the central office, and the mechanism at the central office by which this may be effected. Fourth. Means at the central office for automatically recording the time 30 a signal is received from an outlying station usually called a "time stamping" device. Fifth. Means at the outlying station for attracting the attention of the patrolman when 35

40 in the vicinity of the station, either visibly or audibly and which when necessary will respond to a code of visual or audible signals;—together with the office mechanism by means of which such signals may be actuated from the central station. Sixth. Means at the central office for designating by signals to the 45

50 stable where the patrol wagons are kept,—the outlying station to which the wagons or ambulance are to be brought when so required and the necessary apparatus at the stable to indicate and record such signals. Seventh. Telegraph mechanism at the stable

and at the central office for independent signaling between these two places. Eighth. Telephonic mechanism at the stable and at 55 the central office for holding conversation between these two points.

Now the object of my invention is to combine a set of mechanism in an arrangement of circuits by which all these requirements 60 may be attained, and do this with as little complication of circuits and apparatus as possible.

With the exception of some switch connections more fully described hereinafter, the 65 apparatus shown as forming the elements of the combinations is either old and well known, or else the subjects of former patents of mine, or applications for the same by me and which will be referred to more particularly hereinafter. The apparatus shown is therefore to be considered as a type of the kind required rather than otherwise, as any other device or machine that will perform the functions of one of those shown may be used instead. 70

75 My invention therefore consists in such a novel arrangement of apparatus and electric circuits connecting the same as by its means citizens or the members of a police department are enabled to communicate with each 80 other, and the movement of the policemen be directed from headquarters by those in charge as already indicated;—the whole arrangement constituting a complete police system of signaling and communication as al- 85 ready stated.

80 My invention further consists in such novel details of switch devices and connections as are necessary to make the system operative and complete and which will be hereinafter 90 more fully described.

I will now describe my invention in detail, referring to the drawings in which similar letters refer to similar parts throughout the several views.

95 Figure 1, shows a general diagram plan of the whole invention in which a complete set of central office apparatus is shown, an outlying station equipped with a full set of station devices and also a stable outfit,—the 100 whole being shown in complete circuit connection. Fig. 2, shows a top view of a novel switch device for making the signals by breaking the circuit and it also shows how

the telephonic connections with the circuits are made at the central office. Fig. 3, is a full sized vertical sectional view of the central office switch device showing the circuit breaking mechanism in its normal position and also showing how the office telephonic connection is made with the outlying station box circuit. Figs. 4 and 5, show how the circuit breaker opens the box circuit and thus 10 gives signals on the bell in the outlying box while it keeps the circuit closed through the office register and thus preventing the latter together with the mechanism which it controls from operating when such signals are sent out. Fig. 6, shows an electric gas light 15 flashing device that may be used to give visual signals in the night time at the outlying station.

A, represents an outlying signal station provided with a box A', containing a set of apparatus consisting of a multiple call box mechanism A², a signal key A³, a bell mechanism A⁴, and a telephone apparatus A⁵, all being 20 of any of the well known forms of devices of this character.

B, represents a closed electric circuit provided with a battery B', and having connection with the call box A², the key A³, the bell magnet A⁴, and a branch wire B², in which 25 the telephone apparatus A⁵, is placed and which has a ground connection through a resistance or condenser C. At the central office the circuit B, is from the battery B', through the register magnet D, the "answer back" 30 switch D', the wire B³, the contact spring D², the insulated wheel D³, and the contact spring D⁴, of an "answer back" machine then through the wire B⁴, through the register switch D⁵, and the wire B⁵, to the middle 35 terminal spring E, of the telephone switch device E', through the upper terminal spring E², of the device E', and the wire B⁶, through the outlying station mechanism as already described to the battery B'. By this arrangement 40 it can be seen that whenever the call box circuit is opened by means of the circuit breaker A², or the key A³, at the outlying station A, it will cause the register magnet D, at the central office to record such signals and actuate such other signal devices as 45 may be controlled by the register magnet. When the middle spring E, of the switch device E', is depressed by means of the button E³, at the central office, however, it will only 50 open the circuit beyond that point as it makes contact with the lower spring E⁴, see Fig. 4, before it breaks contact with the upper spring E², see Fig. 5, and the lower spring E⁴, having a short circuit wire connection B⁷, with the 55 battery B', the circuit is thus kept closed through the register magnet D, and the latter remains inactive while the bell magnet A⁴, gives the signals at the station as the button E³, is manipulated at the central office. This 60 constitutes one of the novel features of this invention when taken in connection with the other central office mechanism of a police sig- 65

nal system and this whole arrangement constitutes the telegraphic means of signaling between the station and central office;—automatically, by means of the call box device A², and manually by the key A³, at the station A, and the spring key E, at the office, the magnet A⁴, sounding the signals at the station, and the magnet D, at the office, actuating such 70 signaling and recording devices as may be connected therewith.

The middle telephone switch spring E, extends upwardly at its back end and makes a contact with a tooth E⁵, on a contact wheel E⁶, which is mounted upon a shaft E⁷, having a loose bearing in a sleeve E⁸, which is secured in a hole in the frame E⁹, by means of the nut E¹⁰. An index E¹¹, is secured upon the upper end E¹², of the shaft E⁷, by means of a 75 nut E¹³. The dial plate E¹⁴, is provided with figures 1, 2, 3, &c., to indicate the circuit that is in connection when the index is in registering position therewith. The wire B⁸, which is secured to the lower end E¹⁵, of the shaft E⁷, by means of the nut E¹⁶, is connected through the telephone set F, and resistance or condenser C', with the ground G. The wheel E⁶, is incased with an insulating shell E¹⁷, upon which the end E¹⁸, of the contact spring E, rests when the tooth E⁵, is not in contact therewith. The shape of the tooth E⁵, and the shell E¹⁷, as well as the manner in which the tooth E⁵, and the contact spring E, makes connection, is shown in Fig. 2. It can therefore be seen that by moving the index E¹¹, to cause the wheel E⁶, to make connection with the spring E, that the telephone F, becomes placed in circuit connection with the telephone A⁵, the ground forming part of the circuit, and that oral communication can be held between the station A, and the central office, as the circuit can be traced either over the wire B⁵, or else through the spring E², and the wire B⁶.

One of the calls of the multiple call box A², is usually intended to indicate through the register magnet D, at the central office and the register mechanism and tape D⁵, and bell D⁶, that it is desired to hold oral communication, 115 hence the register magnet D, gives the requisite telephone calling up signals at the central office. Corresponding calling up signals can be given upon the bell A⁶ of the magnet A⁴, at the outlying station by depressing the 120 spring E, of the central office switch device E', by means of the button E³, see Fig. 3. The key A³, may also be used at the outlying station to give calling up signals to the magnet D, upon the office mechanism. The magneto devices shown in connection with the telephone sets A⁵, and F, may also be used 125 for calling up signals.

D⁷, represents the shaft of a machine to indicate through the bell magnet A⁴, after a report signal has been sent in from the station A, that it is desired that the officer making his report shall call up the central office through the telephone A⁵ and report for special in-

structions. This device usually gives such a signal after the report call has been sent in to the central office and is intended to do this automatically, whenever the officer makes his 5 regular report, provided the proper switch connections are made with the circuit to accomplish this end; hence, immediately after the report call has been sent in from the station the officer hears this special signal upon 10 the bell A⁶, of the magnet A⁴, immediately after his own signals are completed, so that it appears as though it was that his own signal was answered back, hence the name of the device. The means by which this is effected will now be described. The armature lever D⁸, is provided with an insulated relay contact D⁹, which closes an open circuit D¹⁰, through the time stamp magnet H, which causes the time stamp H', of the time stamp 15 device H², to make an impression of the time the signal is received, upon the tape D⁵. The magnet H, also causes the shaft D⁷, of the "answer back" machine to revolve and as notches in the wheel D⁸, pass beneath the contact spring D², the circuit B, becomes 20 broken and signals are given through the bell magnet A⁴. The time in which the shaft D⁷, makes its complete revolution is a trifle longer than the time in which the call box circuit 25 wheel A², makes its revolution and the notches in the wheel D⁸, are so arranged upon the shaft D⁷, as to break the circuit D, after the circuit wheel A², has completed its signal and before it completes its own revolution. The 30 spring D², is shown as adapted to pass over two notches in the circuit wheel D⁸, hence two taps will be given upon the bell device A⁴, and by throwing the switch D', on the terminal D¹¹, so as to send the circuit through 35 the branch wire B³, and the contact spring D¹², a single tap will be given upon the bell A⁶, as there is but one notch which passes under this spring. This whole time stamping machine and "answer back" device is 40 fully described in application for Letters Patent filed by me March 7, 1891, Serial No. 384,172, and to which reference may be had. If it is desired that no "answer back" signals be given to the outlying signal bell A⁶, 45 this can be accomplished by bringing the switch D', upon the terminal D¹³, and thus cut out of circuit the whole "answer back" mechanism so that the use or non use of the "answer back" device is entirely controlled 50 by the manipulation of the switch D', and the "answer back" and time stamping service can be thus understood without further description.

Attention is called to the fact that the armature lever D⁸, of the register magnet D, 55 serves as a relay by means of the contact D⁹, and gives signals upon the bell D⁶, as this combination of mechanism controlled by the single magnet D, taken together with the other magnet H, which also controls the action of the time stamp device and "answer back" machine is a novel feature in police central

office signal mechanism, as I believe all this service has never been heretofore obtained by such a simple combination of magnets and 70 mechanism.

It is sometimes necessary to secure the attention of an officer while patrolling upon his beat in the vicinity of an outlying station, and the means by which I accomplish this 75 will now be described. Station A, is usually provided with some method of illumination at night, either gas or electric light. If gas is to be the illuminant the device shown in Fig. 6, may be used, while if an electric light 80 is to be used it may be put directly into the circuit I, instead of the device shown in Fig. 6. In this latter case however the circuit I, should be entirely a metallic one instead of grounded at the station for purposes of 85 safety. The circuit I, is provided with an electric generator I', and a switch I², by which the circuit may be opened or closed as desired at the central office. A circuit closer J, is also provided by means of which the circuit I, 90 may be closed or opened automatically so as to give a code of signals over the circuit I, and thereby cause the gas light magnet I³, through its armature I⁴, to partly close the valve I⁵, in the gas fixture I⁶, see Fig. 6, and 95 thus diminish the supply of the gas giving the light. This diminution of the light by regular intervals may be understood according to a code already established and to accomplish this regularly and automatically, the device 100 J', is provided which controls the movement of the circuit closer J, through the circuit J², and the magnet J³, having the generator J⁴. The device J', may be any kind of a mechanical or electrical device that will control 105 the movements of the circuit closer J, and the one herein shown and described may be more clearly understood by reference to Patent No. 335,027 for electric signals granted to me on January 26, 1886. The circuit closing device 110 J', is shown as controlling the movements of four circuit closers J, J⁵, J⁶, and J⁷, which are adapted to control the signals to be given over the light signal circuits I, I⁴, I⁵, and I⁶, to the stations K, K, K. It must be understood 115 however that any other device that will control the currents by means of the movements of the circuit closers J, J⁵, J⁶, and J⁷, will answer the purpose as well as the device herein shown and referred to as I do not wish to 120 limit myself to the use of this particular device. The circuit I, is shown as being grounded beyond the station A, and the circuit closer J, is shown as being adapted to make another ground connection through the branch I⁷, 125 with the ground thus completing the circuit through the ground when the metallic part of the circuit is closed by means of the circuit closer J, and the switch I². By this whole arrangement it can be seen that 130 whenever the officer in charge at the central station desires to attract the attention of an officer in the night time visually but silently who may be patrolling in the vicinity of the

station A, and by whom the light thereon would ordinarily be seen it is only necessary to set the signal device J', so as to cause it to give the proper signals over the circuit I, upon the light at the station and to maintain the same in operation until the patrolman's attention would be attracted when he would understand the meaning of the signal thus given and could act accordingly. In the day time the bell I⁸, may be used if audible signals are desired to be given instead of the silent signals as at night. If a silent signal is desired in the day time instead of the audible one given by the bell I⁸, this may be accomplished by substituting therefor a semaphore device I⁹, or any other visual signal device such as is used in giving signals to railroad trains or the like and which may be of any of the well known forms of construction as now in use or that might be devised for giving signals of this character and which are controlled and actuated by electro magnetic devices and which respond to impulses of an electric current sent over a circuit from some distant point. It can also be understood that by closing the circuit I, by means of the switch I², and the circuit closer J, for an indefinite length of time that a permanent signal can be maintained upon the circuit I, such for instance, as would be indicated by the permanent (for the time being) diminution of the gas light I⁶, or the light of the electric lamp I¹⁸, or the constant position maintained by the semaphore device I⁹ or the constant ringing of the bell I⁸. If a bell is to be used in connection with any of the visual devices already referred to, it ought to be so constructed that the circuit would not be broken as with the ordinary vibrating bell mechanism. Such devices however are of well known construction:—a vibrating armature which only short circuits the magnet in vibrating bell devices or an electro mechanical gong which is wound up would answer this purpose and which can be understood without further description. It can also be understood that such an electric impulse as has already been referred to as passing over the circuit I, could also cause various other signal devices, such for instance, as a glass globe, or disk with suitable electro magnetic trip mechanisms to pass in front of or around the light and thus give a permanent signal if the glass were of a suitable color, such for instance, as red or green or the like. From the foregoing it can be seen that a variety of means is provided by which the attention of the patrolman may be secured when in the vicinity of the station A, and this done by the operator on duty at the central office.

When a signal has been sent in from an outlying station that the wagon or ambulance is needed the operator at the central office communicates with the driver or other person in charge of the stable by means of the devices which will now be described.

L, represents a multiple signal device adapt-

ed to give a number of signals corresponding to the numbers of the outlying signal stations over the circuit L', in which is placed a register magnet L², adapted to control the pen mechanism L³, of the register L⁴, and in which is also placed the bell magnet of the bell mechanism L⁵, upon which the signals are sounded. The indicator L⁶, is also placed in the circuit and by means of which the number of the station may be indicated in plain figures. The bell mechanism L⁵, and the indicator L⁶, are of the well known construction ordinarily adapted to give fire alarm signals and can be understood without further description. The signal device L, may also be of any of the well known forms of construction or for instance, like that shown in my application for Letters Patent for an improvement in electric signal devices filed March 16, 1891, Serial No. 385,300, and to which reference may be had. The mechanism shown as being placed in the circuit L', is adapted however to give and receive only such automatic signals as are within the capacity of the transmitter L, hence for oral communication or independent telegraphing between the central office further devices are provided, which will now be described.

M represents a circuit having a connection with the switch device E', at the central office and in which one of its keys E¹⁹, is placed. Another key M' is placed in the circuit M, at the stable and so arranged as by its manipulation to cause signals to be sent over the circuit through the magnets M², and M³, and to thereby cause the signals to be sounded on the bells M⁴, and M⁵. The manipulation of the key E¹⁹, will of course also cause similar signals to be given upon the bells M⁴, and M⁵, and in this way signals can be transmitted telegraphically between the central office and the stable in which the bell magnets M³, and M², are placed respectively. A telephone apparatus N, is placed in the stable having a branch connection N', with the circuit M, and also a ground connection N², through a condenser, or resistance C. By this arrangement oral communication may be had at any time between the central office and the stable providing the suitable switch connection is made through the switch device E'. The magneto bell mechanisms of the telephone apparatuses F, and N, will answer for "calling up" signals for telephone purposes but they may be omitted and the keys E¹⁹, and M', and the bells M⁴, and M⁵, may be also used for "calling up" purposes. The register magnet L², as well as the gong mechanism L⁵, and indicator mechanism L⁶, may be looped into the circuit M, and the multiple transmitter L, likewise placed in circuit and the battery L⁷, be dispensed with, and the whole mechanism be controlled by the single battery M⁶, if so desired as the circuit L', is shown as a separate circuit instead of a loop for purposes of clearness. The manner in which this can be done is indicated by the

switches O, O', which are shown as placed each side of the battery L⁷. It can be seen that by throwing these switches as indicated by the dotted lines that the circuit L', would 5 then become a loop in the circuit M, and the battery L⁷, might be entirely removed and all of the mechanism located at the stable would thus be placed in a single circuit and in direct connection with the central office switch 10 device E'. The complete stable apparatus is understood as comprising the register magnet L², with its mechanism,—the bell L⁵, and the indicator L⁶, the magnet M², with its bell mechanism,—the key M', and the telephone 15 apparatus N.

The operation of the system will now be explained: When a patrolman on his beat comes to the outlying station A, he manipulates the call box mechanism A², within the box A', so 20 as to report to the central office that he has reached the station A, in going around on his beat. The signal thus given by the signal mechanism A², is sounded upon the bell A⁶, in the station A, and also causes the magnet 25 D, to register upon the tape D⁵, the number of the outlying station A, and also the characters indicating the nature of the call and the individual member of the department thus making his report. Attention is also called 30 to the fact that a signal is coming in by the sound of the bell D⁶, which is also actuated by the signal. The circuit closer D⁹, also closes the circuit D¹⁰, through the magnet H, and the latter actuates the time stamp H', 35 which is connected to the L shaped armature lever H³, which carries the armature of the magnet H. The tape D⁵, passes between the presser H', and the time characters of the time stamp device H², and thus causes the 40 time that the signal is received to be imprinted upon the tape D⁵. A suitable inking device forming a part of the time stamp mechanism H², is arranged between the presser H', and the time characters so as to make 45 the time imprint more legible and which may be either on the upper or under surface of the tape D⁵, as may be desired. The shaft D⁷, carries a wheel D¹⁴, but which is insulated therefrom which is provided with one 50 tooth D¹⁵, upon which the contact springs D¹⁶, and D¹⁷, rest when the shaft D⁷, is in its normal position. But as soon however as the first break in the circuit B, occurs the tooth D¹⁵, of the wheel D¹⁴, leaves contact with 55 one of the springs D¹⁶, and D¹⁷, and the circuit D¹⁰, remains open between these springs notwithstanding the closures made by the circuit closer D⁹, in response to the subsequent breaks in the circuit B, made by the 60 call box mechanism A², in giving its complete signal. In this way the presser H', makes only one imprint upon the tape D⁵, notwithstanding the numerous closures made by the circuit closer D⁹, while the complete signal 65 is being registered upon the tape D⁵. The armature lever H³, controls the movement of the shaft D⁷, by means of the detent D¹⁸,

which is secured thereon. If the call thus sent in from the station A, be simply a "report" call, the officer on duty in the central 70 office is made aware of it, by the operation of the register mechanism and the time stamp device, as already indicated, and nothing further is necessary on his part but to allow the patrolman to proceed on his beat and turn in 75 another similar "report" call from the next outlying station he comes to, and in this way the regular "report" calls are turned in from any number of stations that may be in the system, and by any number of policemen who 80 are thus on duty. If a patrolman however should desire to hold oral communication with the officer in the central office, he gives the signal upon the call box A², corresponding to such a desire on the part of an officer 85 which is sounded upon the bell D⁶, and recorded upon the tape D⁵, and is so understood by the officer on duty in the central office. The latter then depresses the key E³, of the switch device E', which causes the 90 magnet A⁴, to indicate upon its bell A⁶, that he is ready to talk with the officer at the outlying station at the same time he moves the index E¹¹, of the switch device E', so as to connect the telephone apparatus F, through the 95 branch B⁸, with the circuit B. The patrolman can then use the telephone apparatus A⁵, and talk to the central office officer through the central office telephone apparatus F, and the latter can likewise talk back through the apparatus F, and the apparatus A⁵, to the patrolman and in this way special instructions or information may be given and received orally between the patrolman and the central 100 officer.

The box A', in the outlying station A, is usually so constructed that a citizen desiring to communicate with the police office can have access to but one of the calls that can be given therefrom, and this is done automatically in a manner similar to that in which the patrolman makes his report call. The officer on duty in the central office signals back through the magnet A⁴, on its bell mechanism the reception of such a signal which the citizen can hear and understand as indicating that a signal has been received and his wish for police assistance, or the like, complied with, using the key E³, of the switch device E' to do this. Now if either of the calls from the 110 citizen, or the policeman, would be understood as requiring the use of the patrol wagon, or ambulance, the central officer would give such a signal either automatically, by means of the signal device L, which would indicate upon 115 the indicator L⁶, or the gong L⁵, or the tape of the register mechanism L⁴, the number of the outlying station to which the wagon, or ambulance, was to be brought. If some special 120 instructions were to be given, however, this could be done either telegraphically, by means of the key E¹⁹, of the switch device E', which would be sounded upon the bell M⁴ at the stable, or else oral communication regarding 125 130

the matter could be held by means of the telephone apparatuses F, and N, in the usual manner of telephonic communication. If the attendant at the stable should desire to telegraph back to the central officer, he could do it by manipulating the key M', which would sound its signals upon the bell M⁵, at central office. Now it will be supposed that a patrolman should signal in from another outlying station P, for instance, that he desired the assistance of officers who were patrolling in the neighborhood of station A, he accordingly sends in the appropriate signal upon the mechanism in the box P, which is similar to that described and shown as belonging to station A. The officer on duty at the central office observes such a signal upon the tape D⁵, and accordingly sets the circuit closing device J', so as to give signals over the circuit I, corresponding to the number of the station P, and starts it into operation. The circuit closer J, then makes the appropriate closures of the circuit I, which causes the gas light device I⁶, to flash, or flicker, so as to indicate silently but visually the number of box P, and the officer or officers patrolling in the vicinity of station A, would observe the light signals given by the device I⁶, and would understand that they were wanted immediately at station P, to which they could go direct. This method of police signaling in this connection is novel, and advantageous, as hitherto, the signals usually given at signal stations from police headquarters have only a single meaning which is,—that the officer report at the station A, first, and then receive instructions as to where he is to go. The reason of this, is,—that only signal contrivances that will either cause a colored glass shade to pass in front of the light, or some other signal of a single meaning, has heretofore been ever used, and devised, for this purpose. Now by my system I can give a code of signals of an indefinite number, and great variety, which can be distinguished from each other, and which when observed, or heard, convey some special meaning, or significance, to the patrolman who sees, or hears, them. The advantages of this system are very great, and numerous, and in the illustration shown, its importance can be seen; as the policeman when he sees or hears one of these signals can at once go where his services are required without losing the time incidental to a system in which he would first be obliged to go to the station where the signal was given, and then learn either telegraphically, or orally, what was required of him. Of course it is understood that the switch I², would have to be thrown upon the terminal of the circuit I, so as to establish a complete circuit. It may also be seen that whether the closures of the circuit I, by means of the circuit closer J, operate a bell mechanism, an electric lamp, or a semaphore device, the nature of the signals will be the same as these various devices are referred to, simply for the purpose of illustrating how a

code of signals may be given either visually, or audibly, over the circuit I, by means of the operation of the circuit closer J.

Now the signal sent in from the station P, by the patrolman there might indicate a riot, for instance, and which would call for the assistance of not only the patrolman in the vicinity of station A, and several other similar stations throughout the city, but also the patrol wagon and such officers as would be available at the central office. In this latter case the mechanism at the stable would be manipulated by means of the switch device E', or the multiple signal device L, in the manner already described, and the whole police force so far as it was available, could be quickly concentrated at the station P. In this way the nature and importance of the combination of all of the elements in the system is shown, constituting as it does, the call box mechanism at the outlying station by means of which, the emergency call is given, and the register and time stamp mechanism, in the central office upon which it is received and recorded, the signal circuit I, having the various signal devices therein, by means of which, the other patrolmen are signaled to, that their services are at once required at station P, and the circuit closer J, with its automatic actuating device J', by means of which, the signals are transmitted and repeated in an orderly and regular manner, and the mechanism at the stable comprised in the circuits M, and L', by means of which, the signals may also be given to the stable attendant, and the central office mechanism by means of which, these devices are controlled and actuated. The circuits I⁴, I⁵, I⁶, have signal devices which are not shown, but are to be understood as being similar in construction and operation to those shown in circuit I, and are provided with circuit closers I¹⁰, I¹¹, and I¹², by means of which, any one of the circuits may be made to operate similar to the operations of the circuit I, by the movements of the circuit closer J. The circuit closers J⁵, J⁶, and J⁷, perform the same functions for the circuits I⁴, I⁵, and I⁶, respectively, that the circuit closer J, performs for the circuit I, and which can be readily understood without further explanation. The object of showing the three extra circuits I⁴, I⁵, and I⁶, which are each supposed to have signal devices like those shown in circuit I, is to show, how outlying stations K, K, K, may be grouped in different circuits which would go through different parts of the city, and so that a system of attracting signals could be divided, by the manipulation of the switches I², I¹⁰, I¹¹, and I¹², and the signals thus given, limited to the territory in which it was desired to have such signals operate, while at the same time leave some other of the circuits, (or parts of the city) free from the effects of such signals:—in other words give the signals to policemen in some parts of the city, for instance, those near the scene from which the "emergency"

call was given, and leave other of the patrolmen undisturbed by the effects of such an alarm, on account for instance, of the remoteness from which they were from the station to which the rest of their fellow members were called. The stations K, K, K, are each supposed to be equipped with a call box mechanism, signal bell and telephone apparatus, like that shown as belonging to station A. They are supposed to have a signal mechanism similar to those shown as belonging to station A, and which are placed in the signal circuit I. For purposes of clearness, however, the call box circuits corresponding to the circuit B, in which the call box mechanisms are placed, are omitted, but they can be understood as being similar to the circuit B, or for that matter the circuit B, might be extended so as to pass through all of them. I wish it therefore to be understood, when I refer to station A, that taken as a whole, it is a device from which the call box mechanism connects with the central office, by means of the circuit B, and the signal mechanism shown as adapted to be used in the circuit I, is also connected therewith, and by means of the circuit I, with the central office mechanism controlled by the device I', which is located at the central office. In the same way, the mechanism shown as belonging at the stable is also, taken as a whole, another element in the system.

The expression "central office" refers to a police head-quarters, and is used more particularly to designate the apparatus located thereat, and with which connections are made, rather than as being an element, or thing itself, in the combinations.

The purpose and operation of the "answer back" mechanism, will now be explained:— Suppose it is desired that the patrolman when he arrives at the outlying station A, in making his rounds, after making his "report" call, shall then remain at the station and put himself in telephonic communication with the officer on duty at the central office, and that it is desired to communicate this information to him automatically, from the central office, upon the station bell mechanism A⁶, immediately after his report signal has been completed. When the central office officer decides to do this, he at once manipulates the switch D', so as to bring the branch B⁹, with its terminal spring D¹², the circuit wheel D⁸, and the branch wire B⁴, with its terminal spring D⁴, into the main call box circuit B. The effect of this will be that when the circuit wheel D⁸, revolves, (which it does every time a signal is sent in) one of the notches in passing under the spring D¹², will cause a break in the circuit and consequently cause a single tap to be given upon the bell A⁶, in the signal station. Now this tap will occur immediately after the call box device A², completes its signal, in the manner previously described, and the officer when he makes his "report" call, listens while his "report" sig-

nal is being sounded upon the bell A⁶, and when he hears the additional stroke upon the bell he at once understands that he is expected to report orally to the central office and await special instructions. If the connection of the switch D', be with the branch B⁸, having the spring D², resting upon the wheel D⁸, then two taps will be given upon the bell A⁶, as there are two notches in the wheel D⁸, which pass under the spring D². The significance of either one of these "answer back" taps are of course understood by the patrolman, and he acts accordingly, as for instance, the double tap might be used to denote that he was expected to at once report in person at the central office without waiting for any special instructions from the officer on duty there. This "answer back" service might be varied and increased according to the requirements of the department as can be understood without further explanation. Or again the reception of the "answer back" taps upon the bell A⁶, may also be used to signify that the incoming signals have actuated the office mechanism and been recorded there and the operation of the "answer back" device of itself, would indicate that the mechanism had duly responded to the incoming signal. Another object attained by this "answer back" mechanism is this:—It is customary for the officer at the central office to allow the report signals to come in and register themselves automatically, without any act on his part other than to recognize their reception, but as soon as he decides that the patrolman is to be instructed specially, he at once manipulates the switch D', and then he need pay no further attention to the matter of having the patrolman report for special instructions at the outlying station, knowing as he will, that whenever the patrolman hears the special "answer back" signal, he will report for instructions even though the interval of time between that at which the former manipulated the switch D', and that at which the latter reports, be comparatively great. Hence the commanding officer might temporarily absent himself from the central office, after he had manipulated the switch, and still if the patrolman should report during this absence, he would understand this and remain at the outlying station until he could receive the orders that were intended for him.

What I claim, and desire to secure by Letters Patent, is—

1. The combination with an outlying signal station provided with a call box mechanism and an attractive signal device a circuit having connection with the call box mechanism a magnet D, of a register mechanism having a connection with the call box circuit and adapted to indicate the signals at a central office that are given by the call box mechanism, and also another circuit having connection with the attractive signal device a circuit closer connected with the attracting sig-

nal circuit adapted to actuate from the central office the attractive signals at the outlying station an automatic device adapted to automatically control the movements of the 5 circuit closer and of other similar circuit closers, other circuit closers having corresponding connections with attractive signal circuits and in which are placed other attractive signal devices at other signal stations in the system all combined substantially as specified.

2. The combination with an outlying signal station provided with an attractive signal device having a circuit connection with a circuit closing device at a central station, and being provided with a call box mechanism, a circuit having a connection with the call box mechanism a magnet D, of a register central office mechanism, an armature mechanism D⁸, 15 adapted to be controlled by the magnet D, and being provided with a circuit closer D⁹, a circuit D¹⁰, having a connection with the circuit closer D⁹, and a magnet H, in the circuit D¹⁰, and an armature lever mechanism 20 H³, which is actuated by the magnet H, and which is provided with a presser H', and the time stamping device H², against which the presser H', makes impressions substantially as specified.

3. The combination with the circuit B, of the call box mechanism A², and the bell magnet A⁴ at the outlying station and the register magnet D, at the central station the armature mechanism D⁸, of the magnet D, provided with the circuit closer D⁹, the circuit D¹⁰, having a connection with the circuit closer D⁹, and being provided with the terminals D¹⁶, and D¹⁷, and the magnet H, of an answer back mechanism, the armature mechanism 40 H³, of the magnet H, the shaft D⁷, of an answer back mechanism provided with the detent D¹⁸, which is controlled in its movement by the armature mechanism H³, and which is provided with the insulated circuit wheel D¹⁵, 45 which is adapted to close the circuit D¹⁰, between the terminals D¹⁶, and D¹⁷, and the shaft D⁷, being also provided with a notched insulated circuit wheel D⁸, the terminals D², and D¹², which rest upon the circuit wheel D³, and 50 which are provided with wire connections B⁸, and B⁹ respectively, the switch D', having a connection with the circuit B, and adapted to switch the current over either of the circuits B⁸, or B⁹ respectively and a terminal spring 55 D⁴, which also rests upon the wheel D³, having the wire connection B⁴, by means of which a loop of the circuit B, may be extended through the circuit wheel D⁸, of the answer back device taken in connection with the 60 wires B⁸, B⁹, and having a switch D⁵, which is adapted to complete the loop with the circuit B, and thereby enable the circuit wheel D³, to break the circuit B, and thereby cause signals to be given through the magnet A⁴, upon 65 its bell mechanism at the outlying signal station all in the manner above specified.

4. The combination with the circuit B, hav-

ing a call box mechanism A², and a bell magnet A⁴, therein a loop consisting of the wires B³, and B⁴, which is provided with terminals D², and D⁴, and the notched wheel D³, of an answer back mechanism and a switch D', by means of which the loop is established through the answer back mechanism substantially as specified. 75

5. The combination of the following the circuit B, provided with call box mechanism A², and magnet A⁴, of the outlying station and the magnet D, of the central office register mechanism the armature mechanism D⁸, of the magnet D, provided with the circuit closer D⁹, the circuit D¹⁰, having connection with the circuit closer D⁹, and the magnet H, connected in the circuit D¹⁰, which is provided with an armature mechanism adapted to actuate a combined time stamping device and answer back mechanism substantially as specified. 85

6. The combination with a circuit B, having therein a call box mechanism A², of a magnet D, and an armature mechanism D⁸, which is adapted to actuate a combined time stamp and answer back mechanism consisting of the circuit D¹⁰, the time stamp device H², and the answer back mechanism D⁷, and 95 also the bell mechanism D⁶, substantially as specified.

7. The combination with the circuit B, of the call box mechanism A², and the bell magnet A⁴, and the telephone apparatus A⁵, connected by means of a branch wire B², all at the outlying station the register magnet D, provided with the armature mechanism D⁸, adapted to record signals given by the call box mechanism A², upon a tape D⁵, and also 105 sound signals upon a bell mechanism D⁶, a switch device E', provided with a key mechanism E, E², E⁴, having wire connections B⁵, B⁶, B⁷, with the circuit B, and being also provided with a circuit closer E⁵, adapted to 110 make connection with the terminal E, of the key mechanism, and the branch wire B⁸, having a connection with the circuit closer E⁵, and in which is placed the telephone apparatus F, all substantially as specified. 115

8. The combination with the circuit B, of a call box mechanism A², and bell magnet A⁴, of an outlying signal station A, a magnet D, adapted to indicate the signals of the call box mechanism A², a switch device E', in circuit 120 connection with the circuit B, provided with key mechanism E, E², E⁴, so constructed that the closing of the circuit between the terminals E, E⁴, is effected before the contact between the terminals E, E², is opened and 125 thereby adapted to open the circuit B, at the outlying station and cause signals to be given through the bell magnet A⁴, while the circuit is kept closed through the magnet D, and thereby preventing the operation of the armature mechanism D⁸, substantially as specified. 130

9. The combination of the circuit B, provided with a call box mechanism A², and bell

- magnet A⁴, at an outlying signal station, and a magnet D, adapted to actuate a register mechanism at a central office a switch device E', provided with key mechanism E³, adapted 5 to give signals upon the bell magnet A⁴, at the outlying station and being also provided with a key mechanism E¹⁹, a circuit M, having connection with the key mechanism E¹⁹, of the switch device E', and a bell magnet M², 10 of a stable apparatus in the circuit M', that is adapted to give signals upon a bell M⁴, whenever the key mechanism E¹⁹ of the switch device E', is manipulated substantially as specified.
- 15 10. The combination of the following elements; the circuit B, having therein a call box mechanism A², at an outlying station the register magnet D, of a central office register mechanism a switch device E', provided with 20 key mechanisms having a circuit breaking connection with a circuit consisting of a section M, and the loop L', and the circuit consisting of the section M, and the loop L', containing therein the bell magnet M³, and the 25 multiple transmitter L, at the central office and the register magnet L², the key M', the bell magnet M², and the gong L⁵, and indicator L⁶, at the stable all combined substantially as specified.
- 30 11. The combination of the following elements; a circuit B, provided with a call box

A², at an outlying station and a register magnet D, at the central station a switch device E', provided with key mechanisms and a circuit M, L', having connection with the switch 35 device E', a magnet L², and an automatic multiple transmitter L, in circuit connection with the switch device E', through the circuit L', M, all combined substantially as specified.

12. The combination of the following ele- 40 ments; an outlying signal station A, provided with an attractive signal device having a circuit connection with an actuating circuit closer J, at a central office and being also provided with a call box mechanism having 45 a circuit connection with a register mechanism D, at the central office a switch device E', having connection with the call box circuit a circuit M, L', also having a connection with the switch device E', and a stable mech- 50 anism consisting of the register mechanism L², the gong L⁵, and indicator L⁶, and the multiple automatic transmitter L, arranged at the central office in circuit connection with the register magnet L², the gong L⁵, and indicator L⁶, constituting the stable apparatus all 55 combined substantially as specified.
